UNITED STATES PATENT OFFICE.

WILLIAM ESCAMILLA, OF MEXICO, MEXICO, ASSIGNOR, BY MESNE ASSIGNMENTS, TO
TAB-EDGED SYSTEM, INC., A CORPORATION OF NEW YORK.

CARBON OR COPYING PAPER.

Application filed September 29, 1924. Serial No. 740,458.

This invention relates to improvements in carbon or other copying paper for the purpose of enabling one or more sheets of such paper to be readily and expeditiously withdrawn from between sheets of typewriting or other writing or letter paper after the desired impressions have been made, to the end that the carbon or copying paper can be separated for subsequent use.

10 It is the usual practice when making one or more carbons to use carbon or copying paper of a size substantially coextensive with the paper on which the impressions are to be made and since the copying substance is more or less sticky or tacky in character, the separation of the sheets after impressions have been made constitutes a time consuming annoyance which it is the object of the present invention to obviate.

15 To this end, the invention consists in associating with one edge of the sheet of carbon or copying paper a tab or projection adapted to extend sufficiently beyond the edges of the associated sheets of writing or typewriting paper to be readily grasped for the purpose of withdrawing the carbon paper from between the sheets of paper on which the impressions have been made, while maintaining both sides of sheets individually in alinement. To facilitate this withdrawal of the carbon or copying sheets the tab is preferably formed near one corner of each sheet of carbon paper while the diametrically opposite corner is preferably 20 cut away to a limited extent, so that the writing and typewriting sheets may be gripped firmly together at its corner while the tabs of the several carbon sheets are grasped and said latter sheets withdrawn.

25 30 35 40 This permits the sheets of each set to be kept in alinement.

In practice, the tabs or projections of the carbon or copying sheets are left white. They are not coated with the copying substance, so that the sheets may be handled by these tabs without soiling the hands of the operator.

Of considerable practical importance is the novel shaping of the tabs or projections, 50 as well as the cut outs at the opposite corners of the carbon paper. The tabs or projections are so shaped that they will be devoid of weak points which might result in inadvertent tearing away of the tabs. The proportioning of these tabs and their shap-

ing are carefully worked out to give a structure of maximum strength. Moreover, the shaping of such tabs is such as to eliminate the possibility of tearing them from the body of the sheets when passing the assembled carbon and typewritten sheets through a typewriting machine. I have further so proportioned the tabs as to give a visible indication of the position of the paper in the machine whereby the operator using carbon paper embodying the present invention is notified of the approach of the bottom of the sheet through the appearance of one portion of the tab and is subsequently or at a subsequent line on the typewritten page 60 65 70 notified by the appearance of another portion of the tab that the last line has been reached. This greatly facilitates the work of the operator in keeping track of the position of the sheets in the machine and lends 75 to uniformity of work.

Features of the invention, other than those specified, will be apparent from the hereinafter detailed description and claims, when read in conjunction with the accompanied drawings.

The accompanying drawings illustrate one practical embodiment of the present invention, but the construction therein shown is to be understood as illustrative, only, 80 85 and not as defining the limits of the invention.

Figure 1 shows the preferred embodiment of the invention; and,

Figure 2 shows a modified form of the 90 invention.

Referring to the drawings, 1 designates a sheet of carbon or other copying paper, one surface of the body of which is coated with a suitable transferring medium. In 95 general respects the body of this sheet is substantially identical with the carbon paper known to the art.

The invention consists in associating with one edge of the sheet a tab 2, which is preferably located at the lateral edge of the sheet and adjacent one corner thereof. The opposite corner of the sheet is preferably cut away as shown at 3, the shape of this cut out portion being preferably substantially one fourth of an ellipse. The purpose of so shaping the cut out 3 and proportioning it as shown in the drawing, is to make this cut out substantially conform to the contour of a finger tip so that when 100 105 110

a number of carbon sheets, such as shown in the drawings, are interposed between corresponding typewriting or letter sheets, the juxtaposed corners of the letter sheets may 5 be firmly gripped and held together in assembled relation without gripping the contiguous portions of the carbon sheets. In practice, this cut out 3 may be omitted and the sheet continued out to the corner as usual, or, if desired, the sheet may be perforated along the line 3^a, as shown best in Figure 2 so that the portion corresponding to the cut out 3 may be readily torn out by the ultimate purchaser in the event that the 10 operator desires to utilize this feature of the invention. In practice, however, I prefer to make the sheets with the cut outs 3 as shown in the drawing.

The tab 2, which is located at the diametrically opposite corner from the cut out 3 is carefully shaped and proportioned to fulfill a number of functions. It is made of sufficient length to provide a proper grip for the fingers and is so shaped that it affords no sharp corners or weak spots at which tearing would be apt to occur. It is to be noted that the upper portion of the tab is cut on the line 4 which has such angular relation with the adjacent edge of 20 the sheet 1 that the upper edge of the tab is sloping. This slope is carefully worked out to give a definite relationship between the sloped portion 5 and the vertical lateral edge 6 of the tab. In practice, the top of 25 the vertical portion 6 is located at a distance Y from the bottom of the sheet which distance is preferably in practice the distance which the last line of typewriting should occupy from the bottom of a typewritten sheet, while the sloped portion 5 is 30 of such height that the distance Z is equal to the vertical spacing of one or more superimposed lines of typewriting on a typewritten sheet. When the parts are thus proportioned, the operator will know that when 35 the inclined portion 5 first comes into view in alinement with a line of typewriting that sheet will have space for a predetermined 40 number of additional lines on the sheet 45 on which impressions are being made.

When, however, the operator observes 50 that the line which she is writing is in alinement with the upper end of the vertical portion 6 of the tab, that this line is the last 55 line of typewriting that should be put on a sheet. Inasmuch as the tab is positioned in close proximity to the end of a typewriting line, the operator cannot fail to observe 60 these relative positions and thus uniformity of several successive sheets of typewriting is assured.

Another important advantage of shaping 65 the upper edge of the tab as shown resides in the fact that when thus shaped the tendency of the tab to catch while passing

through a typewriter is obviated since the sloping edge will guide the tab in such manner as to preclude tearing thereof.

In practice, the tab is left uncoated so 70 that the operator may grasp the same without soiling the fingers. The use of carbon paper embodying the present invention will be apparent from what has been stated and it will be manifest that after impressions have been made on assembled typewritten 75 and carbon paper sheets and these sheets removed in assembled relation from the machine, the carbon sheets can be readily separated from the typewritten sheets by grasping the upper left hand corners of the assembled sheets in one hand, care being taken 80 to grasp the immediate corner of the sheets so that pressure will be applied in the zone of the cut outs 3 of the carbon sheets. If the tabs of the various carbon sheets are collectively grasped by the other hand and slight tension exerted in opposite directions, the carbon sheets will be withdrawn from the typewritten sheets leaving all of the typewritten sheets in alinement and all of 85 the carbon sheets in alinement, and this operation is accomplished expeditiously and without soiling the operator's hands.

In the preferred manner of carrying out 90 this invention, the tab 2 is preferably 95 formed integral with the body of the sheet 1. It is within the purview of the invention, however, to perforate along the base of the tab as shown at 7 in Figure 2 so that, if desired, the tab may be torn off. It is 100 also within the purview of this invention to form the tab separately from the material of which the sheet is formed and to glue or otherwise adhesively secure the tab to the body of the sheet 1.

As I have hereinbefore stated, the tabs of 105 the carbon paper sheets are preferably left uncoated although, if desired, they may be coated without departing from the spirit of this invention. It is also within the purview of this invention to leave the tabs uncoated and color them in some contrasting color so that they will be more readily visible.

Having thus fully described the invention, 110 what I claim as new and desire to secure by Letters Patent is:

1. Carbon or copying paper provided at 115 one corner with a tab extended beyond the lateral edge of the sheet in longitudinal direction and having its upper edge inclined downward and outward and its lower edge rounded.

2. Carbon or copying paper provided at 120 one corner with a tab projected beyond the lateral edge of the sheet and extended in the direction of the length of the sheet, said tab 125 extending to the end of the sheet and having its upper end tapered, thus being constructed to serve a triple function, namely,

to preclude tearing away of the tab, to notify the typist of the approach of the bottom of the sheet being written upon, and then to indicate the approach of the last line to be written upon.

3. Carbon or copying paper provided at one corner with a tab extending in the direction of the length of the sheet and beyond the lateral edge of said sheet, with its upper end

10 at an angle to the lateral edge of the sheet,

the distance between the top and bottom edges of the angled portion being equal to the distance between two lines of type-writing, and the lower edge of such angled portion being such as to indicate that but one ¹⁵ line only can be written on the sheet.

In testimony whereof I have signed the foregoing specification.

WILLIAM ESCAMILLA.
